TWIN WINDOW FAN UNIT

Ralph E. Evarts, Wichita, Kans., assignor to The O. A. Sutton Corporation, Inc., Wichita, Kans., a corporation of Kansas

Application January 14, 1954, Serial No. 28,515

Term of patent 14 years

(Cl. D62—4)

FIG. 1

FIG. 2

FIG. 3

To all whom it may concern:

Be it known that I, Ralph E. Evarts, a citizen of the United States of America and a resident of Wichita, county of Sedgwick, State of Kansas, have invented a new, original, and ornamental Design for a Twin Window Fan Unit, of which the following is a specification, reference being had to the accompanying drawings, forming a part hereof.

Fig. 1 is a front elevation view of a twin window fan unit embodying my new design;

Fig. 2 is a plan view of Fig. 1;

Fig. 3 is an end elevation of Fig. 1;

Fig. 4 is a front elevation of the unit with both fans in reversed position from the showing in Figs. 1, 2 and 3; and

Fig. 5 is an end view of the unit with both fans inclined upwardly and inwardly.

I claim:

The ornamental design for a twin window fan unit, as shown.
